ATTORNEY

UNITED STATES PATENT OFFICE.

ANDREW STARK, OF CHICAGO, ILLINOIS.

HARVESTING-MACHINE.

SPECIFICATION forming part of Letters Patent No. 355,728, dated January 11, 1887.

Original application filed August 4, 1883, Serial No. 102,762. Divided and this application filed August 18, 1885 Serial No. 174,698. (No model.)

To all whom it may concern:

Be it known that I, ANDREW STARK, a citizen of the United States, residing at Chicago, in the county of Cook and State of Illinois, have invented certain new and useful Improvements in Harvesting-Machines, which are fully set forth in the following specification.

This application is a division of my application filed August 4, 1883, No. 102,762.

The invention consists in certain novel features of construction adapted to secure in a harvesting-machine frame rigidity and compactness of structure, as hereinafter described, and set forth in the claims.

In the drawings, Figure 1 is a plan of my harvester-frame. Fig. 2 is a front elevation of the same. Figs. 3 and 4 are respectively a rear elevation and a stubble-side elevation 20 of the inner segment, showing its connection with the finger-bar and main frame.

A is the main-frame bar, formed, preferably, of angle-iron, extending in a single continuous piece partly around the driving-wheel 25 from the point 1 by way of the angles 2, 3, 4, and 5 to the point 6. From the point 3, near the intersection with the draft-pole, this frame has the portion *a* extending diagonally backward in a direct line to the point 2, near its 30 junction at 1 with the finger-bar A⁷, and thence crosses the latter at right angles, in order to afford a rigid junction therewith, the two parts being firmly bolted together at said junction. The finger-bar A⁷, also preferably

35 formed of angle-iron, is rigidly secured also at 8 to a suitable bracket, c², formed on the inner segment, C². The bar A⁴ is bolted to the frame-bar A at the points 14 and 9, and to the segment C² at 16 and 17, and at 19 it is bolted 40 to the bracket c² at the end of the segment C², the bolt at the last-named point also passing through the finger-bar A⁷ at the point 8, and thus further securing it to the bracket. The bar A⁵ is bolted to the frame-bar A at 10 and 45 at 6, and to the finger-bar A⁷ at 11. The rear sill, A⁶, crosses and is secured to the cross-bar A⁵ at 7, and thence extends to the cross-bar A⁴, to which it is secured at 13.

The parts thus far described constitute the 50 main frame, adapted to carry the usual driving, cutting, and conveying mechanisms, and

an automatic binder, whose frame, supporting and containing the usual table and mechanism of such machines, is designed to be secured to the said main frame above the bars 55 A⁴ and A⁵, in the rear of the line of the finger-bar A⁷. This main frame is sustained upon the driving-wheel C and the grain-wheel b, the design being as nearly as possible to balance the frame on these wheels, the pole upheld by 60 the horses and locked rigid with the frame constituting a third support.

The main frame is sustained upon the driving-wheel in the usual manner by means of the segments C' and C'', secured to the frame, and 65 the pinions C²⁰ on the axle of the driving-wheel engaging with the racks on said segments. The outer segment, C', is fastened to the frame-bar A, and the inner segment, C'', is bolted to the end of the finger-bar and to the 70 cross-bar A⁴, as above described.

The draft-pole A⁹ is locked to the main frame rigidly, but preferably made capable of adjustment. I prefer to give it its principal attachment to the frame at or directly above the 75 stubble end of the finger-bar, and for that purpose I provide the hinge F, one member of which, F', is bolted directly to the finger-bar and the other member, F'', is firmly secured to the end of the pole. The form of each member is adapted to the shape of the part to which it is to be secured, and the details of structure of the hinge are such as fit the hinge to serve 80 certain purposes in adjusting the machine.

From the hinge F the pole extends slightly 85 upward over the frame-bar A, near to the cross-bar A⁴, and under the iron loop F², which is secured to the frame-bar A and to the cross-bar A⁴. Near the loop F² the pole is adjustably locked to the frame-bar A⁴. 90

The advantages of the several features of construction above described I will now state, in order that it may be understood what details are material and what may be varied without losing the advantages which it is the purpose of this invention to secure. 95

First. By extending the finger-bar toward the drive wheel and joining it directly to the inner segment, said inner segment being rigidly and directly joined to the main frame, and the main frame and finger-bar being also rigidly bolted together at their intersection, both the 100

segment and the finger-bar are very securely braced and further serve to stiffen the frame, and particularly the segment which guides the drive-wheel is thereby enabled to keep 5 the gear-rim of the latter properly in mesh with the driving-pinion, whose bearing will be obtained on the main frame; hence, however the forms and proportions of the parts may be varied, the above-stated features of 10 construction should be retained.

Second. The main frame, the inner segment, and the finger-bar being thus mutually interconnected, the draft-pole, connected to the finger-bar near its junction with the segment 15 and near to the junction of the segment with the frame, will draw the machine with the least possible tendency to strain any of its joints or distort any of its shafts or cramp them in their bearings.

Third. The diagonal portion *a* of the frame-bar *A* being in approximately a direct line from the junction of said frame-bar with the finger-bar to its intersection with the pole under the loop *F*² enables the machine to be 20 turned by means of the pole with the least possible tendency to sag the cutter-bar or wrench the frame.

The mechanism for adjusting the platform and the relation of the pole thereto, herein 30 partly shown and described, are the subject of my said application No. 102,762, filed August 4, 1883, and the same are not herein claimed. Neither do I claim herein the inner segment finger-bar and grain-wheel guide all 35 rigidly secured together, as partly shown herein, because I have claimed such structure in my application No. 147,143, filed November 3, 1884.

I claim—

1. In a harvesting-machine, the combination of a rigid main frame adapted to carry the driving mechanism, the inner segment axle-guide, and a rigid finger-bar, each of said parts secured rigidly to both the others, substantially as and for the purpose set forth.

2. In a harvesting-machine, the combination of an iron frame extending around the front outer side and rear of the drive-wheel, a cross-bar at the inner side of said wheel rigidly secured at front and rear to said iron frame, the inner guiding-segment for the main axle secured rigidly to said cross-bar, and the finger-bar rigidly secured to both said cross-bar and said guiding-segment, substantially as set forth.

3. In a harvesting-machine, the combination

of an iron main frame rigidly secured to the finger-bar and extending thence around the front outer side and rear of the drive-wheel, a cross-bar at the inner side of said wheel rigidly secured at front and rear to said iron frame, and the inner guiding-segment for the main axle rigidly and directly secured to both the finger-bar and the said cross-bar, substantially as set forth.

4. In a harvesting-machine, the combination of an iron frame extending around the front outer side and rear of the drive-wheel, a cross-bar at the inner side of the wheel and rigidly secured at front and rear to the said iron frame, and the inner guiding-segment for the main axle secured rigidly and directly both to the finger-bar and the cross-bar, substantially as set forth.

5. In a harvesting-machine, the main frame consisting of the continuous iron bar *A*, having the portion *a* extending diagonally from a point near the intersection of said bar with the draft-pole to a point near the finger-bar, the cross-beams *A*⁴ and *A*⁵, bolted rigidly to said bar *A*, and the finger-bar *A*⁷, rigidly secured to the said iron bar near the end of the diagonal portion *a*, and to the said cross-beams, substantially as and for the purpose set forth.

6. In a harvesting-machine, the main frame consisting of the continuous iron bar *A*, secured at one end to the finger-bar near the heel of the cutter-bar, thence extending in an approximately direct course to its intersection with the draft-pole, and thence around the front outside and rear of the drive-wheel, in combination with the cross-beams *A*⁴ and *A*⁵, secured to the front and rear portions of said iron bar *A*, the finger-bar *A*⁷, and the rear sill, *A*⁶, the last two being secured to both of said cross-beams, substantially as and for the purpose set forth.

7. In a harvesting-machine, the rigid main frame supported at one end directly upon the main axle, segment axle-guides rigidly secured to the frame, the finger-bar rigidly and directly secured to the inner segment-guide, and a pole connected to the finger-bar and locked rigid with the main frame, all combined and operating as and for the purpose set forth.

In testimony whereof I have hereunto set my hand, in the presence of two witnesses, at Chicago, Illinois, this 30th day of June, A. D. 1885.

ANDREW STARK.
